(57) **CLAIM**

The ornamental design for a grillwork, as shown and described.

DESCRIPTION

FIG. 1 is a perspective view of a grillwork shown within the environment of a truck bumper. Broken lines in the drawing depict environmental subject matter that forms no part of the claimed design;

FIG. 2 is a perspective view of a grillwork;

FIG. 3 is a front view of a grillwork;

FIG. 4 is a rear view of a grillwork;

FIG. 5 top view of a grillwork;

FIG. 6 is a bottom view of a grillwork;

FIG. 7 is a left side view of a grillwork; and,

FIG. 8 is a right side view of a grillwork.
